Primary Examiner — Samantha Q Lawrence*Assistant Examiner* — Thanh Luu Wong(74) *Attorney, Agent, or Firm* — Own Innovation Inc.; James W. Hinton(57) **CLAIM**

The ornamental design for a rowing machine, as shown and described.

DESCRIPTION

FIG. 1 is a perspective view of a rowing machine; FIG. 2 is a front view thereof;

FIG. 3 is a rear view thereof;

FIG. 4 is a right side view thereof;

FIG. 5 is a left side thereof;

FIG. 6 is a top view thereof; and,

FIG. 7 is a bottom view thereof.

The broken lines in the drawings illustrate the portions of the rowing machine that form no part of the claimed design.
